FINNED TUBE

Edward G. Lehman, York, Pa., assignor to York
Ice Machinery Corporation, York, Pa., a cor-
poration of Delaware

Application April 15, 1937, Serial No. 137,102

5 Claims. (Cl. 29—157.3)

This invention relates to refrigeration, and more particularly to heat exchange units of the finned coil type.

One object of this invention is to provide a finned coil which may be assembled on the job from a single straight length of tube stock, and a section or sections cut from a length of fin stock, such fin stock including a plurality of fins secured in spaced relation to each other and forming a unitary structure of any desired length.

Another object is to provide a finned coil which may be assembled as above indicated and wherein the fin section or sections are locked in place upon their individual runs of the coiled tube by expanding the tube.

Another object is to provide a finned coil, the fins of which are so formed and connected together prior to their application as fins that accurate alignment and spacing thereof is assured before and after they are locked to the tube, and a substantially stiff structure as a whole is finally produced.

An important advantage incident to the practice of this invention, is that stock lengths of tubing, and stock lengths of fin assembly may be kept available at the point of use and there made up into complete units of various dimensions in accordance with the requirements of the particular installation.

Other objects and advantages will become apparent to those familiar with the art to which this invention relates as the following specification is read in connection with the accompanying drawings, in which.

Fig. 1 is a perspective view of a portion of a fin section constructed in accordance with this invention.

Fig. 2 is a perspective view of a header plate.

Fig. 3 is a longitudinal sectional view showing a portion of a length of tube with two fin sections and their header plates loosely mounted thereon and prior to the bending operation.

Fig. 4 is a transverse sectional view on the line 4—4 of Fig. 3, a portion of the header plate being broken away to expose a part of the fin structure. The clearance between the tube, and header plate and fins encircling the same, is exaggerated in the drawings. Actually a sliding fit is made between the elements.

Fig. 5 is a fragmentary sectional view showing the edges of two fins and the means of securing the spacing ribbon strip to them.

Fig. 6 is a side elevation of a completed unit. Fig. 7 is a plan view thereof.

Fig. 8 is an end elevation of the same.

Fig. 9 is a view similar to Fig. 4, the tube having been expanded to bring it into intimate frictional or locked engagement with the fins and header plate.

Fig. 10 is a detail of a form of rivet used to secure the adjacent header plates to one another.

Referring to Fig. 1 of the drawings, the numeral 11 indicates a group of fin plates constructed and assembled in accordance with this invention. Each fin 12 comprises a thin rectangular shaped plate stamped to include stiffening ribs 13, and apertures 14 formed centrally thereof.

Any desired number of fins 12 are assembled in spaced relation by means of a plurality of metal ribbon strips 15. Each of these strips 15 is crimped at equidistant points throughout its length to form pockets 16 which receive the corners of the fin plates 12 and make a snug fit therewith. The parts are secured together by indenting or embossing, as is clearly shown at 17 in Fig. 5 of the drawings. Other means for securing these parts together, such as soldering, may be adopted though that indicated has been found satisfactory and is preferred.

A unitary fin assembly is thus produced wherein the fins are accurately spaced and aligned and secured against casual displacement. It can be readily cut into sections of any desired length 30 by simply severing the ribbon strips 15 at the proper point. Stock units may be made up of any desired length and cut to different lengths or different stock lengths may be provided.

Peripherally flanged header plates are associated with each group of fins 12 when the coil and the fins are assembled. Fig. 2 of the drawings shows such a header plate and by reference thereto it will be seen to comprise a rectangularly shaped plate 18 apertured at 19, similarly 40 to the fin plates 12, and provided with a peripheral flange 21 also apertured as at 22.

For illustrative purposes in Figs. 6 to 8, a coil having six straight runs or passes has been chosen. It is to be understood however that coils of any desired dimensions and number of passes may be made up by proper selection of the length of tube and the number of fin sections per group and number of groups.

In practicing this invention a length of tube 50 23 is cut from the straight tube stock. From the fin stock, sections or groups of fin plates of the required length and number (six sections in the instant case) are cut and threaded upon the tube by passing the tube through the aligned

openings 14 in the individual fins 12, see Fig. 3.

Header plates 18, one at each end of each group of fins 12, are included, the tube 23 passing through the apertures 19 formed therein.

- 5 Both the header plates 18 and the fin plates 12 make a sliding fit with the tube 23. It is entirely practicable, and in some instances may be desirable, to finally position the fins and header plates at this point. This may be done by expanding the tube by any of the well known methods, such as hydrostatic pressure or, by simply forcing an expanding tool through the tube. The fin sections and their associated header plates are, of course, spaced from one another 10 to provide a free section of pipe for the return bends of the coil, and are accurately located at their calculated positions prior to such expanding operation.

If it is elected to expand the tube by hydrostatic pressure prior to bending it, a support such as a 20 jig or the like will be necessary to protect against over-expansion those portions of the tube forming the return bends. However, the preferred method is as follows:

- 25 The tube 23 having the fins 12 and header plates 18 properly spaced and positioned thereon is bent to form a coil of the prescribed dimensions. The fin sections 12 will now be parallel with each other and being loose upon their respective passes 30 of the coil may be shifted longitudinally thereof to effect any final adjustment necessary to accurately align the various groups. Similarly, the flanged header plates 18 are brought into juxtaposition with their adjacent flanges 21 contacting, 35 and the perforations 22 therein being aligned. These header plates 18 are now secured to each other by means of rivets 24, see Figs. 8 and 10. As shown most clearly in Fig. 10, the rivet used comprises a head 25 and a hollow shank 26. The 40 shank 26 is inserted through the aligned openings of the adjacent flanges 21 and then peened over as at 27.

With the various elements thus accurately positioned it remains only to bring the fins 12 and header plates 18 into frictional or locked engagement with the tube coil 23. This is effected by 45 expanding the tube 23, utilizing hydrostatic pressure to bring about this result.

An important advantage of expanding the tube 50 subsequent to bending it is that working of the metal at the return bends during their formation hardens or stiffens the metal sufficiently at these points to withstand the pressure incident to the expanding operations. This obviates the necessity of supporting these sections at such time and so simplifies this step in forming the completed coil.

The header plates act to extend the surface of 55 the coil, and to that extent may be considered as fins or the equivalent thereof.

60 While the invention has been described in exact form and detail, no necessary limitation thereto is implied, variations or modifications within the scope of the appended claims being contemplated.

65 What is claimed is:

1. A heat exchange unit of the finned coil type which includes a coil having a plurality of parallel passes formed from a single tube; a group of fins for each pass of said coil, each of said fin groups 70 being a unit composed of a plurality of fin plates connected to each other to form a unitary self-

sustaining fin structure, said sections being applied to said tube by threading thereon; flanged header plates associated one with each end of each of said fin sections by being threaded upon said tube, said fin plates and said header plates being frictionally locked in position by deformation of said tube, the header plates for adjacent passes being aligned; and connections between such aligned adjacent header plates. 5

2. The method of producing finned coils which 10 comprises threading a plurality of units each made up of a plurality of centrally perforated fins and spacing means permanently attached to said fins and adapted to hold the fins in parallel spaced relation to one another, and a plurality of end 15 plates, one end plate at each end of each of said units, upon a continuous length of tubing, said units being separated from each other to afford unfinned intervals between units, bending the tubing in such unfinned intervals to produce 20 parallel finned runs, connecting the end plates of adjacent runs with each other and then while the fins and end plates are maintained in properly spaced relation, expanding the tube to lock the fins and end plates in heat exchanging contact 25 with the tube.

3. A heat exchange unit of the finned coil type comprising in combination a tubular core formed from a single straight length of tube, having imposed thereon groups of rectangular fin plates, 30 each of said groups being formed as a unitary self-sustaining structure; including continuous spacers formed of strips of sheet metal crimped upon the corners of successive fins; header plates one associated with each end of each group of fin 35 plates, said groups of fin plates and said header plates being locked upon the tube by the deformation of the tube and said header plates being connected with each other independently of said groups of fin plates. 40

4. The method of producing a finned coil which 45 comprises preparing at least two fin structure units, each unit comprising a plurality of one-piece fin plates, each fin plate having a tube-receiving aperture and the fin plates of respective units being permanently connected with each other in spaced relation with their apertures aligned by a plurality of slender connecting elements, the connections being such that the unit is self-sustained and substantially rigid; inserting 50 the tube into the aligned apertures of both units; bending the tube between such units to produce adjacent passes; and after such bending expanding the tube to lock the fins of the two units in place on the two passes thus formed. 55

5. That step in the process of fixing spaced apertured fins on a tube in which process the tube is inserted through the apertures in the series of fins and then permanently expanded to fix the fins in place, which step comprises permanently 60 connecting the fins together by slender spacing means which form a part of the finished assembly and which offer no substantial resistance to airflow over the fins in any direction, such connection being made independently of the tube prior 65 to the assembly of the fins with the tube and with sufficient rigidity to maintain the spacing of the fins and their alignment during the expanding operation. 70
